DESIGN FOR A FINGER TOOTHBRUSH

Roderick G. Stevens, Chicago, Ill.

Application February 23, 1935, Serial No. 55,588

Term of patent 14 years

To all whom it may concern:

Be it known that I, Roderick G. Stevens, a citizen of the United States, residing at Chicago, Cook County, Illinois, have invented a new, original, and ornamental Design for a Finger Tooth Brush, of which the following is a specification, reference being had to the accompanying drawing, forming part thereof.

Fig. 1 is an enlarged side elevation of the finger tooth brush, showing my new design.

Figs. 2 and 3 are opposite end views.

Fig. 4 is a top plan view.

I claim:

The ornamental design for a finger tooth brush as shown.

RODERICK G. STEVENS.
